[57] CLAIM

The ornamental design for a table, as shown and described.

DESCRIPTION

FIG. 1 is a top plan view of a table showing my new design;

FIG. 2 is a front elevational view thereof, the rear being a mirror image thereto;

FIG. 3 is a right side elevational view thereof, the left side being a mirror image thereto; and

FIG. 4 is a sectional view taken along section line 4—4 on FIG. 2.
